Des. 215,038

Patented Aug. 19, 1969

215,038

PADDLE BOAT

Robert H. Reeder, 301 S. Nimbus Ave., and Billy R. Peak,
15097 63rd St., both of Clearwater, Fla. 33516

Filed Feb. 29, 1968, Ser. No. 10,789

Term of patent 7 years

Int. Cl. D12—06

U.S. Cl. D71—1

FIG. 1 is a view in front elevation of the paddle boat,
FIG. 2 is a rear elevation thereof,
FIG. 3 is a top plan view,
FIG. 4 is a view in side elevation, and
FIG. 5 is a view in perspective.

The dominant features of our design reside in the portions shown in full lines.

We claim:

The ornamental design for a paddle boat, as shown and described.
